UNITED STATES PATENT OFFICE.

AUGUSTUS F. PRIEST, OF DENVER, COLORADO.

RAILWAY-SPIKE.

SPECIFICATION forming part of Letters Patent No. 637,525, dated November 21, 1899.

Application filed February 23, 1899. Serial No. 706,550. (No model.)

To all whom it may concern:

Be it known that I, AUGUSTUS F. PRIEST, a citizen of the United States, residing at Denver, in the county of Arapahoe and State of Colorado, have invented certain new and useful Improvements in Railway-Spikes, of which the following is a specification, reference being had therein to the accompanying drawings.

The invention relates to railway-spikes; and the principal object of my invention is to provide a spike that will produce no more friction during the operation of driving than the ordinary spike and will have a considerably-greater amount of holding power after it is driven within the tie.

With this object in view my invention consists, essentially, of a spike having a movable section formed in its shank, said section constituting a complementary portion of the shank, whereby the friction in driving will be no greater than in the ordinary spike and means for projecting outwardly from the shank the lower portion of said section at the latter end of the driving movement, thereby forming an abutment at the lower end of said spike constituting an additional resistance to the vertical pull exerted by the rail.

The invention further consists in the peculiar construction, arrangement, and combination of the various parts of the spike, as will be more fully hereinafter described.

In the drawings, Figure 1 is a perspective view of my improved spike, the movable section thereof being detached. Fig. 2 is a sectional elevation showing the spike partly driven within the tie; and Fig. 3 is a sectional view of the spike, illustrating the latter as entirely driven within the tie.

The reference-letter A designates the spike-shank, provided at its upper end with the overhanging head B and terminating at its lower end in a solid point C. The inner face of the shank below the overhanging head is provided with a longitudinal recess D, extending the entire length of the shank, and the head is preferably provided with a recess E in alignment and communicating with the recess in the shank. At the lower end of the shank the recessed face is notched to form a shoulder F directly above the point and the inclined faces a and b.

The letter G designates the movable sec-

tion, which is fitted within the recess D and constitutes a complementary portion of the shank. The section referred to is in the form 55 of a spline H, provided at one end with a lateral projecting head I. The opposite end of the spline is squared, as plainly shown in Fig. 1, and is provided with lateral wings J and K, upon which are formed inclined faces 60 c d. The spline is arranged within the recess in the manner shown in Fig. 2, with the head I at some little distance below the spike-head and the incline upon the wings engaging with the inclines upon the shank. This relation 65 of parts is maintained during the driving of the spike until the latter end of said driving movement, when the spline is caused to slide within the recessed shank, and through the coöperation of the inclines upon said shank 70 and spline the lower portion of the latter is forced outward, as shown in Fig. 3, constituting an enlargement at the lower end of the spike, which greatly aids in resisting the vertical pull exerted by the rail.

It will be observed from the construction as set forth that simple means have been provided whereby the holding power of the spike is considerably increased, while the friction due to driving is practically the same as in 80 an ordinary spike. It will likewise be observed that a spike of this construction can be more readily withdrawn from the tie than an ordinary spike, as upon the first part of the upward movement the spike proper slides 85 for a certain distance in its upward travel upon the spline.

What I claim as my invention is—

1. In a spike, the combination with the shank terminating at one end in a point adapted to be driven within the tie, and at the opposite end in an overhanging head, said shank having a longitudinal recess formed in the face thereof beneath the overhanging portion of the head, a movable section fitting within 95 said recess beneath the spike-head, said section forming a complementary portion of the shank and constructed to engage with the rail-flange, and means for spreading, during the latter part of the driving movement of the 100 spike, the section and shank.

2. In a spike, the combination of the shank terminating at one end in a point adapted to be driven within the tie and at the opposite

end in an overhanging head, said shank having a longitudinal recess formed in its face beneath the overhanging portion of said head, a movable section fitting within said recess 5 beneath the spike-head, said section being constructed to bear continually against the rail-flange and to engage with the latter, and means for spreading, during the latter part of the driving movement of the spike, the 10 lower portion of the section and shank.

3. In a spike, the combination with a shank terminating at one end in a point adapted to be driven within the tie, and in the opposite end in an overhanging head, said shank having 15 a longitudinal recess formed in its face beneath the head, a spline fitting within the recess and forming a complementary portion of the shank, a head on the spline beneath the overhanging spike-head adapted to strike 20 the rail-flange and hold the spline from movement during the latter part of the driving movement, and means for forcing out laterally, beyond the shank, an abutment at the 25 lower portion of the spike by the movement of the shank relatively to the spline.

4. In a spike, the combination of the shank terminating at one end at a point adapted to be driven within the tie, and at the opposite end in an overhanging head, said shank having 30 the face beneath said overhanging head uniformly recessed, a spline fitting within said recess and forming a complementary portion of the shank, a head on the spline below the spike-head adapted to strike the rail- 35 flange and hold the spline from movement during the latter part of the driving move-

ment, and complementary inclines upon the spline and shank adapted upon the movement of the latter relatively to the spline, to force the lower end of said spline out laterally beyond the shank to form a holding enlargement in the wood. 40

5. In a spike, the combination of a shank terminating at one end in a head and at the opposite end in a solid point, one of the 45 faces of the shank being longitudinally recessed its entire length, inclines formed in said recessed face adjacent to the point, a headed spline within the recess forming a complementary portion of the shank, and inclines formed upon the lower end of the spline 50 engaging and adapted to coöperate with the inclines upon the shank.

6. In a spike, the combination of a shank terminating at one end in a head and at the 55 opposite end in a solid point, one of the faces of the shank being longitudinally recessed its entire length, inclines formed in said recessed face adjacent to the point, a headed spline within the recesses forming a 60 complementary portion of the shank, and laterally-extending wings upon the lower end of the spline having inclined faces formed thereon adapted to engage the inclines upon the shank. 65

In testimony whereof I affix my signature in presence of two witnesses.

AUGUSTUS F. PRIEST.
